[57] ABSTRACT

In a high voltage circuit of a color television receiver, constructed such that the voltage of the secondary winding of a fly-back transformer is converted into high DC voltages by an n -ple voltage rectifier, and that the output voltage E_b of the n -th stage of the rectifier circuit is applied to the phosphor screen of a post-deflection focusing type or after-focusing type Braun tube, while the output voltage E_m of the m -th stage ($m < n$) is applied to the shadow mask thereof, a high voltage circuit wherein a voltage stabilizing element is incorporated between the output terminal of the n -th stage of the n -ple voltage rectifier circuit and ground, and current is kept steadily flowing through the element, whereby the ratio between the voltages E_b and E_m , that is E_b/E_m , is held substantially constant against load fluctuations in the n -ple voltage rectifier circuit.

HIGH VOLTAGE CIRCUIT OF COLOR TELEVISION RECEIVER

BACKGROUND OF THE INVENTION

1. Field of the Invention

The present invention relates to a high voltage circuit of a color television receiver, and more particularly to a high voltage circuit by which the ratio between voltages applied to a shadow mask and to a phosphor screen in an after-focusing type Braun tube is always held constant.

2. Description of the Prior Art

In prior art shadow mask type color television receivers, the transmissivity of an electron beam permeating through a shadow mask is low, and the luminance is accordingly low. In order to raise the luminance, the voltage applied to the shadow mask should be made higher. In consequence, the current to be supplied to the deflecting yoke should be also increased. This is a serious disadvantage of the prior art color television receivers.

Using an after-focusing type color Braun tube as is well known, it becomes possible to enhance the transmissivity of the electron beam permeating through the shadow mask, and to attain a high luminance even if a very high voltage is not applied to the shadow mask itself. In this case, a voltage E_m (approximately equal to the voltage E_f of a funnel portion) which is low as compared with the high voltage E_b of a phosphor screen is applied to the shadow mask. The use of the after-focusing type Braun tube is accordingly advantageous in that the current to be supplied to the deflecting yoke may also be small in comparison with that in the prior art. In the after-focusing type Braun tube, however, it is required to always maintain constant the voltage ratio E_b/E_m between the phosphor screen voltage E_b and the shadow mask voltage E_m ($E_b > E_m$) and the voltage ratio E_b/E_f between the phosphor screen voltage E_b and the voltage E_f applied to the funnel portion of the tube.

The reason is that, when the ratios E_b/E_m and E_b/E_f change due to the variation of luminance by brightness control or to non-uniformity in the characteristic of components, the postdeflection focusing is not effected as predetermined, leading to degradation in the color purity. Only very small changes are therefore allowable for E_b/E_m and E_b/E_f .

FIG. 1 shows a prior art high voltage circuit of a color television receiver. Referring to the figure, numeral 1 designates a fly-back transformer, which has a primary winding 1a and a secondary winding 1b. As is well known, the primary winding 1a has a horizontal deflection output supplied thereto from a horizontal deflection circuit (not shown). A fly-back pulse appears in the secondary winding 1b, and is converted into high DC voltages by means of an n -ple voltage rectifier circuit 2. The n -ple voltage rectifier 2 consists of diodes $D_1, D_2 \dots D_{2n-1}$ and capacitors $C_1, C_2 \dots C_{2(n-1)}$, and the details of the rectifier are omitted herefrom since it is a circuit which has been well known. A higher voltage is provided at an output terminal 2a than at an output terminal 2b of the circuit 2. The voltage E_b derived from the output terminal 2a is applied to a phosphor screen 3a of a Braun tube 3, while the voltage E_m derived from the output terminal 2b is applied to a shadow mask 3b and a funnel portion electrode 3c.

In the above circuit, pulses of a voltage waveform as shown in FIG. 2(A) are produced in the secondary winding 1b of the fly-back transformer 1. The waveform contains a fly-back pulse A and ringing pulses B.

5 The shape and magnitude of the pulses A and B differ in dependence on the characteristic of the fly-back transformer, the construction of the n -ple voltage rectifier circuit, etc. However, even in case where the design is so made as to render the ringing pulses B as small as possible the pulses do not become null but exist, though slightly, on account of dispersions in the leakage inductance of the fly-back transformer, the values of the capacitors of the n -ple voltage circuit, the inductance and capacitance of the primary side of the fly-back transformer, and so forth. In FIG. 2(A), the amplitude of the ringing pulse B is indicated by e_3 .

10 On the other hand, the voltages E_b and E_m , respectively, provided from the output terminals 2a and 2b in FIG. 1 are represented by the following equations:

$$E_b = n e_1 + (n-1)e_2 \quad (1)$$

$$E_m = m e_1 + (m-1)e_2 \quad (2)$$

Accordingly, E_b/E_m becomes:

$$\frac{E_b}{E_m} = \frac{n + (n-1)\frac{e_2}{e_1}}{m + (m-1)\frac{e_2}{e_1}} \quad (3)$$

where

40 n and m are the numbers of stages of voltage multiplication associated with the respective signals, and

e_1 and e_2 are the widths of the pulses in the secondary side winding of the fly-back transformer.

45 As previously stated, the ringing pulses cannot be made null, and therefore they exist, though slightly. Accordingly, when the high voltage load fluctuates, the tuning condition of higher harmonics changes. As illustrated in FIG. 2(B), therefore, the amplitude of the ringing pulse B changes. In consequence, the amplitude of the pulse e_2 changes, the ratio e_2/e_1 changes, and finally the value E_b/E_m in equation (3) changes.

SUMMARY OF THE INVENTION

50 It is accordingly the principal object of the present invention to provide a high voltage circuit which is constructed so that the voltage ratios E_b/E_m and E_b/E_f may be always held constant.

In order to accomplish the above-described object, the present invention consists of a high voltage circuit including a fly-back transformer and an n -ple voltage rectifier device connected on the secondary side of the transformer wherein, when the fly-back transformer is on the third harmonics tuning type, a high voltage stabilizing element is connected between the last stage or an intermediate stage of the voltage multiplication rectifier device and ground.

65 The present invention further consists of a high voltage circuit wherein, when the fly-back transformer is of the fifth harmonics tuning type, a high voltage stabiliz-

ing element is connected between any desired stage of the n -ple voltage rectifier circuit and ground, or the load is connected through a high resistance.

The other objects and features of the present invention will be apparent from the following detailed description when read in conjunction with the accompanying drawings.

BRIEF DESCRIPTION OF THE DRAWINGS

FIG. 1 is a schematic circuit diagram of a prior art 10 high voltage circuit of a color television receiver;

FIGS. 2(A), 2(B) and 2(C) are waveform diagrams of voltages in the secondary winding of a fly-back transformer;

FIGS. 3 and 4 are schematic circuit diagrams each 15 showing an embodiment of a high voltage circuit according to the present invention;

FIGS. 5(A) and 5(B) are regulation voltage characteristic diagrams of voltages applied to the phosphor screen, respectively;

FIGS. 6(A) and 6(B) are waveform diagrams of voltages in the secondary winding of a fly-back transformer in the circuit of the present invention, respectively;

FIG. 7 is a schematic circuit diagram showing another embodiment of the high voltage circuit of the present invention;

FIG. 8 is a diagram of varying characteristics of the respective voltages of a phosphor screen, a shadow mask and a funnel portion of the tube versus the phosphor screen current;

FIG. 9 is a current-voltage characteristic diagram of a voltage stabilizing element;

FIG. 10 is a schematic circuit diagram showing a further embodiment of the present invention;

FIG. 11 is a sketch showing an example of the fly-back transformer for use in the circuit of the present invention, and

FIGS. 12 and 13 are schematic circuit diagrams each showing a still further embodiment of the present invention.

PREFERRED EMBODIMENTS OF THE INVENTION

In FIG. 3, showing an embodiment of the present invention, the same symbols are affixed to the same parts as in FIG. 1, and the explanation of such parts therefore will be omitted. As apparent from FIG. 3, in the circuit arrangement of the present invention, a voltage stabilizing element 4 having a constant-voltage characteristic, such as a Zener diode, is connected between the output terminal 2a of any stage, for example, the final stage of the n -ple voltage rectifier circuit 2 and ground. A DC power source 5 is connected between one end of the secondary winding 1b of the fly-back transformer 1 and ground. A capacitor 23a is also provided for tuning the secondary side of the transformer 1 to the third higher harmonics, while 24 designates a capacitor for making up for the capacity of the phosphor screen 3a.

In the post-deflection focusing type color television receiver, a current I_b flowing through the phosphor screen 3a of the Braun tube 3 and a current I_m flowing through the shadow mask 3b become $I_b = I_m = 0$ when the luminance is minimized. Accordingly, when the luminance is varied from the minimum to the maximum, the output power of the n -ple voltage rectifier circuit 2 fluctuates as stated below.

1. In the case where the high voltage stabilizing element 4 is not included:

$$\text{Output at Minimum Luminance, } P'_{min} = 0$$

$$5 \text{ Output at Maximum Luminance, } P'_{max} = E_b \cdot I_{b \max} + E_m \cdot I_{m \max}$$

2. In the case where the voltage stabilizing element 4 is connected:

$$10 \text{ Output at Minimum Luminance, } P_{min} = E_b \cdot I_n$$

$$15 \text{ Output at Maximum Luminance, } P_{max} = E_b \cdot I_n + E_m \cdot I_m$$

(5)

where I_n denotes a current flowing out from the output terminal 2a to the load.

Usually, $I_n \geq I_{b \max}$, so that

$$20 E_b \cdot I_n > E_m \cdot I_{m \max}$$

(6)

The difference between P_{min} and P_{max} is much smaller than that between P'_{min} and P'_{max} . That is, regarding the load fluctuation with the Braun tube side seen from the n -ple voltage rectifier circuit 2, the circuit shown in FIG. 3 has a load fluctuation which is a great deal smaller than that of the circuit in FIG. 1.

According to the circuit illustrated in FIG. 3, in the 30 case where the same load fluctuation as in the circuit in FIG. 1 arises, the changes of the pulse amplitudes Δe_1 and Δe_2 are smaller, as shown in FIG. 2(C).

The reason is that, since the load current flows steadily through the voltage stabilizing element 4 in the circuit of FIG. 3, the conduction period of the diodes of the voltage multiplication rectifier circuit 2 is longer, with the result that e_1 and e_2 are difficult to change for a given load fluctuation.

In other words, as between the case where the load 40 fluctuation occurs from the state under which the load is zero [FIG. 2(B)] and the case where it arises from the state under which the load current of certain value is already flowing [FIG. 2(C)], the latter naturally provides smaller changes in e_1 and e_2 . As a result, the latter also provides smaller changes in E_b and E_m .

It is therefore possible to restrain the changes of e_1 and e_2 to very small values and to reduce the variation of the ratio E_b/E_m , in such way that a certain load current is previously caused to flow steadily by incorporating the high voltage stabilizing element 4.

In the circuit in FIG. 3, the DC power source 5 is connected between one end of the secondary winding 1b of the flyback transformer 1 and ground. Letting E be the supply voltage of the DC source 5,

$$50 E_b/E_m = n e_1 + (n-1) e_2 + E/m e_1 + (m-1) e_2 + E$$

(7)

60 It is therefore possible to perform the fine adjustment of E_b/E_m by changing E .

Thus, the voltage ratio between the high voltages E_b and E_m ($= E_f$) can be selected at an adequate value, and can be held substantially constant, so that an after-focusing type color television receiver with very stable color purity is realizable.

65 FIG. 4 is a circuit diagram showing another embodiment of the present invention. According to this em-

bodiment, a capacitor 23b adapted to tune the secondary to the fifth higher harmonics is connected on the secondary side of the transformer 1, while a high resistance 4a is connected between the output terminal 2a of the n -ple voltage rectifier circuit 2 and ground.

While the circuit of FIG. 3 employs the fly-back transformer of the third harmonics tuning type, the regulation characteristic of the high output voltage of the voltage multiplication rectifier circuit 2 becomes as shown in FIG. 5(A) in the case of the fifth harmonics tuning type. The regulation characteristic of the high output voltage can be improved as illustrated in FIG. 5(B), in such a way that the high resistance 4a is incorporated as shown in FIG. 4 and that a current I_{b1} is permitted to flow therethrough.

Herein, the high resistance 4a illustrated in FIG. 4 is a mere example of means for taking out a load from the n -ple voltage rectifier circuit 2. In order to achieve the characteristic as illustrated in FIG. 5(B), a high resistance may be inserted between the output of any stage in the n -ple voltage rectifier circuit and ground, so as to take out a load equivalent to $E_b I_{b1}$. Alternatively, a high resistance may be inserted between the output terminals of different stages of the rectifier circuit. In case of incorporating a high voltage stabilizing element, it is more convenient for the measurement of current and other operations that the element be inserted between a DC voltage part and ground.

With the fifth harmonics tuning system, the waveform of voltages in the secondary winding of the fly-back transformer 1 becomes as illustrated by solid lines in FIG. 6(A). In comparison with the third harmonics tuning system with the like voltages shown by broken lines, the fifth harmonics tuning system can reduce the ratio e_2/e_1 between the ringing pulse amplitude e_3 and the fly-back pulse amplitude e_1 . Therefore, when, by way of example, the load current is always kept flowing through the high resistance 4a connected between the output terminal 2a and ground, the input waveform of the voltage multiplication rectifier circuit can be deprived of the ringing pulse amplitude e_3 as shown in FIG. 6(B) even in the case where no current is permitted to flow through the Braun tube 2. Accordingly, even if the load currents I_b and I_m change, changes in e_2/e_1 can be restrained to a very small value.

In a voltage multiplying rectification system of n stages, the ratio E_b/E_m between the voltage-multiplied rectification output E_b and the m -th stage providing the high voltage E_m becomes as the following equation by transforming equation (7):

$$\frac{E_b}{E_m} = \frac{n}{m} + \frac{\left(\frac{n}{m} - 1\right)(e_2 - E)}{me_1 + (m-1)e_2 + E} \quad (8)$$

Herein, n/m necessary for obtaining the ratio E_b/E_m as required becomes a certain fixed value. As the numbers m and n are larger, the denominator of the second term on the right in equation (8) becomes larger with respect to the fixed value n/m , and a variation due to the fluctuation of e_2 becomes smaller. That is, even if e_2 changes due to a change of the load, the change in E_b/E_m will be smaller as m and n are made larger.

Thus, E_b/E_m can be held constant even under the fluctuation of the high voltage load, in such manner that the flyback transformer of the fifth harmonics tun-

ing system is employed, that the high resistance 4a is connected between any stage of the voltage multiplication rectifier circuit and the earth or another stage and that the load is always derived from the flyback transformer 1. In addition, the fine adjustment of E_b/E_m ($= E_f$) can be made in such way that the DC voltage E applied to the lower voltage side of the secondary winding of the fly-back transformer is changed.

In this way, the ratio E_b/E_m between the high voltage 10 E_b and the intermediate high voltage E_m ($= E_f$) can be selected at an adequate value, and it is kept constant even with fluctuation of the load of the high voltage power source, so that an after-focusing type color television receiver which is very stable in color purity can 15 be realized.

The after-focusing type color television receiver can bring a very stable color purity into realization by making the ratio of E_b and E_m ($= E_f$) constant as stated above. However, the beam current of the Braun tube 20 3 strikes the shadow mask 3b and thus creates secondary electrons, so that halation is likely to occur on the screen. In such a case, a voltage higher than the mask voltage E_m is applied to the funnel portion electrode 3c, whereby the secondary electrons are absorbed by the 25 funnel portion and the halation is prevented from occurring.

FIG. 7 is a circuit diagram showing another embodiment of the present invention which has solved the aforesaid problem. According to the embodiment, a 30 voltage stabilizing element 6, such as a constant-voltage diode, and a resistance 7 are connected in series between the m -th stage and the $(m+1)$ -th stage of the n -ple voltage rectifier circuit 2. The output of the 35 voltage multiplication rectifier circuit 2 at the m -th stage is applied to the shadow mask 3b, while the voltage of the juncture between the voltage stabilizing element 6 and the resistance 7 is impressed on the funnel portion electrode 3c. As a result, the funnel portion voltage E_f becomes higher than the shadow mask voltage V_m by a voltage V_6 across the voltage stabilizing element 6.

The series circuit consisting of the voltage stabilizing element 6 and the resistor 7 may also be connected between the m -th stage and any other stage.

In order to stably hold the color purity in the circuit of FIG. 7, the ratio between E_b and E_f should be maintained constant. To this end, $(E_b - E_f)$ may be made constant since the ratio between E_b and E_m is held substantially constant, as previously stated. The voltage difference $(E_b - E_f)$ is kept substantially constant by the voltage stabilizing element 6, so that the ratio E_b/E_f is held constant after all.

When the load of the voltage multiplication rectifier circuit 2 fluctuates, the brightness of the receiver is raised by, for example, increasing the phosphor screen current I_b . Then as shown in FIG. 8, the high voltages E_b , E_f and E_m decrease. As a consequence, the load currents I_f and I_m increase, thereby to reduce a current I_6 flowing through the voltage stabilizing element 6.

The characteristic of the voltage stabilizing element 6 is such that, as illustrated in FIG. 9, the voltage V_6 across the terminals of the element decreases slightly in response to the decrease of the current I_6 flowing therethrough. Therefore, in the case where the high voltage load increases and E_b and E_m decrease, V_6 changes in the direction of keeping E_b/E_f unchanged, and hence, the ratio E_b/E_f is held substantially constant.

Thus, the ratios between E_b and E_m and between E_b and E_f can be selected at adequate values, respectively, and they are constant even with fluctuation of the load of the high voltage power source, so that an after-focusing type color television receiver which is very stable in color purity and free from halation can be realized.

FIG. 10 shows another embodiment of the present invention. As the voltages to be applied to the shadow mask 3b and the funnel portion 3c of the Braun tube 3, desired higher voltages are produced from the voltage of an intermediate stage M of the voltage multiplication rectifier circuit 2.

Referring to the figure, diodes 9 and 10 are connected in series between the intermediate stage M of the n-pole voltage rectifier circuit 2 and the funnel portion 3c. A capacitor 11 is connected in parallel with the diodes 9 and 10.

On the other hand, the voltage between the primary winding 1a of the fly-back transformer 1 and ground is divided by capacitors 12 and 13. The divided voltage is applied through a capacitor 8 to the juncture between the diodes 9 and 10.

The voltage of the primary side of the fly-back transformer 1 may be divided by any other impedance elements. Further, the total voltage may be applied without dividing it.

As a result, there can be obtained, as the output voltage of the diode 10, the voltage E_f of a value with a voltage from rectification of the primary voltage of the fly-back transformer 1 added to the output voltage of the intermediate stage M of the voltage multiplying rectifier circuit 2. In order to more fully stabilize the voltage E_f , a resistor may be connected in parallel with the capacitor 11.

The output voltage of the diode 10 can be arbitrarily varied by changing the division ratio of the primary voltage of the transformer 1. Since only the funnel portion voltage E_f can be varied without changing the output voltage E_b of the voltage multiplication rectifier circuit 2 (the phosphor screen voltage), the ratio E_b/E_f is expressed by the following equation:

$$\frac{E_b/E_f}{V} = n e_1 + (n-1) e_2 + E/m e_1 + (m-1) e_2 + E \quad (9)$$

where V is the DC voltage between the point M and the funnel portion 3c.

As is understood from equation (9), a change in V can vary E_b/E_f more efficiently than a change in the voltage E. Even when the load of the n-pole voltage rectifier circuit 2 fluctuates, E_b/E_m and E_b/E_f are held very stable.

In the circuit of FIG. 10, the pulse voltage to be applied to the capacitor 8 may also be obtained in such a way that the tertiary winding is provided for the fly-back transformer 1, to use pulses induced in the winding.

In this case, the amplitude of the pulses can be controlled through a change in the coupling coefficient by shifting the position of the tertiary winding. Therefore, this method can also vary the ratio between E_b and E_f .

FIG. 11 shows an example of the construction of the transformer in the case where the tertiary winding is provided for the transformer 1 as stated above. Refer-

ring to the figure, numeral 14 designates the iron core of the transformer; 15 is the primary winding; 16 is the secondary winding; and 17 is the tertiary winding. The position of the tertiary winding 17 is moved in the directions of arrows, whereby the coupling coefficients with the other windings change, and the voltage induced in the tertiary winding is also increased or decreased.

Further, two inductance elements are connected in series on the primary side of the fly-back transformer 1, to obtain a divided voltage from the junction point of the inductance elements. Therewith, a winding is wound on the iron core of one of the inductance elements, and a current flowing through the winding is varied, whereby the inductance of the element can be varied to change the voltage division ratio. With such a construction, the voltage V in equation (9) can be continuously changed, and E_b/E_f can be arbitrarily varied as may be needed.

FIG. 12 shows an embodiment as referred to above. Inductance elements 18 and 19 are connected in series on the primary side of the transformer 1. On the same iron core as that of the inductance element 19, an additional winding 20 is wound. A current is supplied from a DC power source 22 through a variable resistance 21 to the winding 20. When the current is varied, the inductance of the inductance element 19 is changed. The value of the voltage to be applied to the junction point of the diodes 9 and 10 can accordingly be changed.

FIG. 13 shows still another embodiment of the present invention. According to this circuit, in order to apply different voltages to the funnel portion 3c and the shadow mask 3b, a potential at one end of the voltage stabilizing element 6 is applied to the funnel portion 3c, while a potential at the other end of the element 6 is applied to the shadow mask 3b. In order to make the ratios E_b/E_m and E_b/E_f variable, there are also provided the capacitors 12 and 13 for dividing the primary voltage of the transformer 1, the diodes 9 and 10 and the capacitor 11 for rectifying and smoothing the divided voltage, etc. With such circuit arrangement, the effects as described with reference to FIGS. 7 and 10 are attained.

What is claimed is:

1. A high voltage circuit for a color television receiver, comprising:
  - a. fly-back transformer means including a primary winding and a secondary winding for producing high voltage pulses from horizontal deflection outputs,
  - b. multiple stage voltage rectifier means made up of double voltage rectifier circuits formed into n stages for producing high DC voltages from the output of said transformer means,
  - c. A Braun tube including a shadow mask, a phosphor screen and a funnel electrode portion,
  - d. means to apply the output of the n-th stage of said voltage rectifier means to said phosphor screen, and means to apply the output of the m-th stage to said shadow mask, where n and m are integers, n being greater than m and greater than 1, and
  - e. means including a voltage stabilizing element connected between an output terminal of an l-th stage, where $(1 < l \leq n)$, of said voltage rectifier means and ground to stabilize the current flowing from said voltage rectifier means through said element to ground, thereby to maintain constant the voltage

ratio between the phosphor screen voltage and the shadow mask voltage.

2. The high voltage circuit according to claim 1, wherein a tuning capacitor for taking out third higher harmonics is connected in parallel with said secondary winding of said fly-back transformer, and wherein said voltage stabilizing element is a Zener diode.

3. The high voltage circuit according to claim 1, wherein a tuning capacitor for taking out fifth higher harmonics is connected in parallel with said secondary winding of said flyback transformer, and wherein said voltage stabilizing element is a resistor having high resistance.

4. The high voltage circuit according to claim 1, further comprising means to apply the output voltage of said m -th stage of said voltage rectifier means to said funnel electrode portion of said Braun tube.

5. The high voltage circuit according to claim 1, wherein a further voltage stabilizing element and a resistance element are connected in series between an output terminal of said m -th stage of said voltage rectifier means and that of the $(m+1)$ -th or later stage, and a voltage across said stabilizing element is applied between said shadow mask and said funnel electrode portion.

6. The high voltage circuit according to claim 1, wherein a variable DC power source is connected between one end of a secondary winding of said fly-back transformer means and ground, so that the supply voltage of said power source can be varied to thereby perform the fine adjustment of the ratio E_b/E_m between the voltage E_b applied to said phosphor screen of said Braun tube and the voltage E_m applied to said shadow mask.

7. The high voltage circuit according to claim 6, wherein a tuning capacitor for taking out third higher harmonics is connected in parallel with said secondary winding of said flyback transformer, and wherein said voltage stabilizing element is a Zener diode.

8. The high voltage circuit according to claim 7, further comprising means to apply the output voltage of said m -th stage of said voltage rectifier means to said funnel electrode portion of said Braun tube.

9. The high voltage circuit according to claim 6, wherein a tuning capacitor for taking out fifth higher harmonics is connected in parallel with said secondary winding of said flyback transformer, and wherein said voltage stabilizing element is a resistor having high resistance.

10. The high voltage circuit according to claim 9 further comprising means to apply the output voltage of said m -th stage of said voltage rectifier means to said funnel electrode portion of said Braun tube.

11. The high voltage circuit according to claim 10, wherein a further voltage stabilizing element and a resistance element are connected in series between an output terminal of said m -th stage of said voltage rectifier means and that of the $(m+1)$ -th or later stage, and a voltage across said stabilizing element is applied between said shadow mask and said funnel electrode portion.

12. In a high voltage circuit for a color television receiver comprising: fly-back transformer means including a primary winding for receiving horizontal deflection outputs, and a secondary winding for producing high voltage output pulses, multiple stage voltage rectifier means made up of double voltage rectifier circuits

formed into n stages for producing high DC voltages from the output of said transformer means, a Braun tube including a shadow mask, a phosphor screen and a funnel electrode portion, means to apply the output of the n -th stage of said voltage rectifier means to said phosphor screen, and means to apply the output of the m -th stage to said shadow mask, where n and m are integers, n is greater than 1 and greater than m , the improvement which comprises a resistor having high resistance connected between an output terminal of the l -th stage ($1 < l \leq n$) of said voltage rectifier means and ground to enable a steady current to flow from said voltage rectifier means through the resistor to ground, means to divide the voltage of the primary winding of said fly-back transformer means, rectifier means to rectify the divided voltage, adder means to add the output voltage of said m -th stage of said voltage rectifier means and an output voltage of the rectifier means, and means to apply the output voltage of said adder means to said funnel electrode portion of said Braun tube whereby to maintain constant the voltage ratio E_b/E_m between the phosphor screen voltage E_b and the shadow mask voltage E_m and the voltage ratio E_b/E_f between the phosphor voltage E_b and the voltage E_f applied to the funnel portion of the tube.

13. The high voltage circuit according to claim 12, wherein said voltage dividing means comprises first and second capacitance elements connected in series between one end of said primary winding of said fly-back transformer and ground, said rectifier means comprising first and second rectifiers connected in series between said l stage output terminal and said funnel electrode and a third capacitive element connected between the point of connection of said first and second capacitive elements and the point of connection of said first and second rectifiers.

14. The high voltage circuit according to claim 12, wherein said voltage dividing means comprises first and second inductance elements connected in series between one end of said primary winding of said fly-back transformer and ground, a winding wound on a core of one of said inductance elements, and means to supply a variable current to the last-mentioned winding, whereby a voltage provided from a juncture between said first and second inductance elements can be changed by varying the current of said winding.

15. The high voltage circuit according to claim 1, wherein said transformer means further comprises a third winding movably wound on a core on which said primary and secondary windings are wound, rectifier means to rectify the voltage induced in said tertiary winding, adder means to add the output voltage of said m -th stage of said voltage rectifier means and the output voltage of the rectifier means, and means to apply the output voltage of the adder means to said funnel electrode portion of said Braun tube, whereby said tertiary winding may be moved to thereby change its electromagnetic coupling coefficients with the other windings, so as to vary the induced voltage in said tertiary winding.

16. A high voltage circuit for a color television receiver, comprising:

1. fly-back transformer means for producing high voltage pulses from horizontal deflection outputs,
2. multiple stage voltage rectifier means made up of double voltage rectifier circuits formed into n

- stages for producing high DC voltages from the output of said transformer means,
3. a Braun tube including a shadow mask, a phosphor screen and a funnel electrode portion,
4. means to apply the output of the n -th stage of said voltage rectifier means to said phosphor screen, and means to apply the output of the m -th stage to said shadow mask, n being greater than m , and

5. means including a voltage stabilizing element connected between output terminals of any different stages of said voltage rectifier means to enable a steady current to flow through said element.
17. The high voltage circuit according to claim 16, wherein said voltage stabilizing element is a resistor of high resistance.
